Inventor:

J. K. Chase

UNITED STATES PATENT OFFICE.

JOHN K. CHASE, OF NEW YORK, N. Y.

IMPROVED METALLIC SCREW-CAP FOR JARS, &c.

Specification forming part of Letters Patent No. 18,498, dated October 27, 1857.

To all whom it may concern:

Be it known that I, JOHN K. CHASE, of the city, county, and State of New York, have invented certain new and useful Improvements in the Manufacture of Caps for Glass, Earthen, and other Jars, Cans, &c.; and I do hereby declare and ascertain my said invention and the mode of constructing the same, reference being had to the following figures of the drawings.

Figure 1 is a view of the cap. Fig. 2 is a section. Fig. 3 is the chuck on which said caps are made.

My improvement consists in forming a thin elastic screw-cap out of a solid piece of sheet metal, by spinning up the same out of a single plate without casting, chasing, or swaging, as has heretofore been done, by which I obtain a cap without joint, seam, or flaw, for covering glass, metal, or earthen cans or jars, the elasticity of the screw serving to fit the unequal threads thereon, and the seamless cap insuring tight joints.

To make my improved caps I take a disk of sheet metal such as I intend to form the cap of, and a little larger than the cap to be formed. This I form over a chuck, such as is shown in Fig. 3. This chuck has upon its periphery a rounded thread, over which the metal cap is spun in the usual way of spinning up other articles of sheet metal, the particular details of which need not be given, as they are well known to operatives in that branch of mechanics.

Having thus set forth my improved article of manufacture, what I claim, and desire to secure by Letters Patent, is—

A screw-cap for bottles, jars, or cans, &c., formed out of a single solid plate of metal by spinning the same over a threaded chuck or former, as above specified, and for the purposes set forth.

JOHN K. CHASE.
